UNITED STATES PATENT OFFICE.

HENRY STAFFORD GOLLAND, OF ECCLES, ENGLAND:

MEANS FOR PRODUCING CROSS-WOUND COPS IN SPINNING MULES AND THE LIKE.

Application filed April 9, 1927, Serial No. 182,256, and in Great Britain July 21, 1926.

These improvements have reference to means for effecting the cross-winding of yarn in spinning mules and such like as the carriage runs in, and of the class described 5 in my United States patent specification No. 1,144,652 and concern advances upon my former British Patents Nos. 22,988 of 1902, 4,848 of 1907, 184,386, 195,018 and 238,804, and for which I did not apply for corresponding 10 United States patents.

These present improvements are developments upon the subject-matter of the former British patents and particularly the last two recited ones:

15 I still use, one, two or more short shafts, carried in a bracket or brackets to support the mechanism from or in connection with the carriage, and I further support the short shafts by other pendent brackets which embrace 20 the winding faller shaft and the cross-winding shaft, thus affording additional support or suspension structures for the short shafts. Instead of actuating the swing bracket directly by toothed gear from 25 the winding faller shaft, as in my prior British specification 238,804, I now operate the same by lever and link mechanism acting on a swing bracket as it is found that due to back-lash following wear a toothed gear 30 interconnection is not entirely satisfactory over a long period. I also provide means to hold or support the swivel plate in a definite position whilst the carriage is running out and spinning, such means being worked by 35 the actuated swing bracket aforesaid by suitable interconnecting means. In order to permit variation of movement or lift of the cross-winding wire I provide for an adjustment of the operated link in a slotted plate 40 which plate is influenced as before by a shaper cam plate. All these features are shown combined in the improved construction hereafter described in detail, and with reference to the attached four sheets of 45 drawings.

Referring to said drawings:

Fig. 1 is a sectional side elevation of one head or an assembly attachment for application to the carriage of a spinning mule, 50 the position of the parts being the bottom position, say when commencing winding of the cop bottom.

Fig. 2 shows a similar view from the opposite hand the position again being that 55 for starting winding. In the Figs. 1 and 2

certain features seen in one view are omitted from the other.

Fig. 3 is a sectional side elevation but with the mechanism in a different position that is the spinning position and not the winding 60 position.

Fig. 4 shows a front view of Fig. 1.

I prefer to use a similar bracket *a* for the head or heads of mechanism according as to whether one, two, or more are used, to 65 that shown and described in my British Patent 238,804, this bracket being bolted to the carriage framing and held by tie bolts *a'* from the bolster rail or otherwise. To further support the short shaft *b* I use 70 brackets or hangers *b'* which embrace the shaft ends and are clipped on the winding-faller shaft *c* and the cross-winding shaft *d*. Lock-nuts *b*² fit the ends of the short shaft *b* and keep the brackets *b'* in place 75 and lock the short shaft and the parts sustained thereby.

Upon the winding faller shaft *c* is fixed a lever *e* and this lever is connected by a pivoted link *e'* pivoted in turn to a swing bracket *f* loose on the short shaft *b*. Loose on the short shaft *b* and fixed to one arm of the main bracket *a* by two distancing pins *g*^x is a disc or wheel *g* cut with teeth at *g*¹ and *g*². Journalled in the swing bracket *f* is a disc *h* which over a portion of its periphery has teeth *h*' and a cam piece *h*². 80

As known from my former recited patents, the winding faller shaft *c* is oscillated due to a bowl supporting the boot-leg running up and down four or more or less inclines on a coppings rail which rail is lowered as known as the cop building proceeds. When the bowl supporting the boot-leg moves up and down on the coppings rail the winding faller shaft is oscillated and the lever arm *e* is influenced and this, through the link *e'* rocks the swing bracket *f* and rotating the disc *h* due to the engagement of the teeth *h*' on the fixed teeth *g*² causes the cam *h*² to act on the bowl *i*' on the swivel plate *i* and thus to rock said swivel plate *i* which is centred on the short shaft *b*. In rocking such swivel plate *i*, the spur pinion *j* is actuated by the fixed ring of teeth *g*² 105 (pinion *j* corresponding somewhat to the parts *f* and *j*² respectively in my former British Patents 230,368 and 238,804) thus working the ratchet wheel *j*' and by pulling on the pawl *o* moving the shaper cam plate 110

k which is fulcrumed at *k'*. As the ratchet is worked in one direction, and the shaper cam plate *k* actuated, then by reason of the play or action of the slot *k²* on the pin *k³* such pin *k³* is moved or influenced. This will be obvious from a study of my former patents. The pin *k³* is fixed in a plate *l* which is centred on the short shaft *b* hence the plate *l* is vibrated indirectly from the lever arm *e*. Consequently, vibratory motion transmitted through the boot-leg lever from the four or more or less inclines on the coppering rail to the winding faller shaft *c* is transmitted to the plate *l*.

15 The plate *l* has a curved slot *l'* cut therein. From this slot is a link connection *m* the same extending from the slot *l'* to a short lever arm *n'* fixed on the cross-winding shaft *d* which carries the cross-winding 20 sickles *n²* and longitudinal cross-winding wire *n³*. By adjusting the position of the lower end of the link *m* in the slot *l'* the amount of movement imparted by the plate *l* to the link *m* lever arm *n'* and cross-winding shaft *d* can be regulated. As a consequence 25 the greater or less movement of the cross-winding wire is provided for without having to vary the depth of the inclines on the coppering rail. A detachable fastening *m'* secures the lower end of the link *m* to the slotted plate *l*. By loosening this fastening and by its adjustment in the slot *l'* and refastening in the required position the throw is regulated. The part *o'* is a spring 30 which influences the pawl *o* and the part *o²* is the device which takes the pawl out of action as the shaper cam plate *k* moves upwards towards the unlocking position. At first, the pin *k³* plays in the radiused part of 35 the slot *k²*, but, when the cop bottom is fully wound, the pin plays in the other part of the slot *k²* moving between the dotted positions *k⁴* and *k⁵*.

In order to ensure the swivel plate *i* always occupying a proper and definite position whilst the carriage is running out, and spinning is taking place, holding means are provided worked from the swing bracket *f* actuated by the lever and link mechanism 40 *e*, *e'*. Such means consist of a bracket *p* centred at *p'* and having a pin *p²* playing in a slot *f³* in the swing bracket *f*. When the bowl *i'* escapes from the cam *h²* due to the downward movement of the outer end 45 of the swivel plate *i* the slot *f³* has influenced the pin *p²* to such an extent as to raise the horned end *p³* of bracket *p* into the position shown in Fig. 3. In this position the horned end *p³* of bracket *p* forms a definite abutment and bears against a bowl 50 *i⁴* on the corner of the swivel plate *i* as clearly shown in the Fig. 3. When winding is taking place, the swing bracket *f* is vibrated as will be understood but does not 55 move to such an extent as to allow the slot

f³ to influence the pin *p²* and therefore the bracket *p* is unlocked and is in the inoperative position as in Fig. 1 and so does not lock or support the swivel plate *i*. When the backing off commences and swing bracket *f* begins to descend the lower extremity 70 of link *e'* encounters the stop *i⁵* and so properly positions the swivel plate *i* (as shown in Fig. 1) which is perfectly held until link *e'* again begins to ascend.

75 The moving parts on the short shaft *b* and between the arms of the bracket *a* are preferably separated by ball bearings as Fig. 4 indicates.

80 The mutilated disc *q* corresponds to the discs *i* and *o* respectively in my former British Patents 230,368 and 238,804 and it is rotated by the pinion wheels *j²*, *j³*, its function being to support the shaper cam plate *k* by acting on the bowl *q'* allowing the bowl to enter the bite until the cop bottom is fully formed. Thereafter, the bowl *q'* bears on the annular periphery to said disc *q*. Thus the disc safeguards the position 85 of the cross-winding wire.

90 The pawl *o* actuates the shaper cam plate during winding and the shaper cam plate controls the cross-winding faller shaft during the actual winding. After the pawl *o* has been disengaged by the projection *o²* before the backing off it is clear that, on releasing the pawl, said pawl slips over the ratchet teeth until it again re-locks at the proper starting position, as will be understood from my former patents.

95 I declare that what I claim is:

1. In a cross-winding attachment for spinning mules, the combination of an oscillatory winding faller shaft, a short shaft supported in parallelism with said faller shaft, a swing bracket mounted for oscillatory movement on said short shaft, and lever connections between said faller shaft and said swing bracket for actuating the latter on the oscillation of the faller shaft.

100 2. In a cross-winding attachment for spinning mules, the combination of an oscillatory winding faller shaft, an oscillatory cross-winding shaft and a short supporting shaft all disposed in parallel relation to each other, means carried by said short shaft for operating said cross-winding shaft, and lever connections between said faller shaft and said operating means for actuating the same.

105 3. In a cross-winding attachment for spinning mules, the combination of an oscillatory winding faller shaft, an oscillatory cross-winding shaft and a short supporting shaft all disposed in parallel relation to each other, a swing bracket mounted for oscillatory movement on said short shaft, lever connections between said faller shaft and said swing bracket for operating the latter, a swivel plate mounted for pivotal movement 110 on said short shaft, operating means car-

- ried by said swing bracket and swivel plate for causing pivotal movement of the latter, and means operated by said swivel plate for oscillating said cross-winding shaft.
- 5 4. In a cross-winding attachment for spinning mules, the combination of an oscillatory winding faller shaft, an oscillatory cross-winding shaft and a short supporting shaft all disposed in parallel relation to each other, a swing bracket mounted for oscillatory movement on said short shaft, lever connections between said faller shaft and said swing bracket for operating the latter, a swivel plate mounted for pivotal movement 30 on said short shaft, cooperating means carried by said swing bracket and swivel plate for causing pivotal movement of the latter, 35 means operated by said swivel plate for oscillating said cross-winding shaft, and automatically operative means for supporting the swivel plate during the spinning operation. 40
- 10 5. In a cross-winding attachment for spinning mules, the combination of an oscillatory winding faller shaft, brackets suspended from said shaft, a short supporting shaft mounted in said brackets, a cross-winding shaft disposed in parallel relation to said faller shaft and short shaft, a swing bracket carried by said short shaft, means 45 between said swing bracket and cross-winding shaft for operating the latter, and lever mechanism between the winding faller shaft and said swing bracket for actuating the bracket. 50
- 15 6. In a cross-winding attachment for spinning mules, the combination of an oscillatory winding faller shaft, an oscillatory cross-winding shaft and a short supporting shaft all disposed in parallel relation to each other, a swing bracket mounted for oscillatory movement.
- 20 5. In a cross-winding attachment for spinning mules, the combination of an oscillatory winding faller shaft, an oscillatory cross-winding shaft and a short supporting shaft all disposed in parallel relation to each other, a swing bracket mounted for oscillatory movement.
- 25 5. In a cross-winding attachment for spinning mules, the combination of an oscillatory winding faller shaft, an oscillatory cross-winding shaft and a short supporting shaft all disposed in parallel relation to each other, a swing bracket mounted for oscillatory movement.

In testimony whereof I have signed my name to this specification.

HENRY STAFFORD GOLLAND.
